Attorney

UNITED STATES PATENT OFFICE.

PAUL C. WOLFER, OF WELLESLEY, MASSACHUSETTS.

LAST.

Application filed July 8, 1927. Serial No. 204,231.

My present invention relates to lasts, and more particularly to an improved last for use in the manufacture of boots and shoes designed to support and correct the foot of the 5 wearer.

An important object of the present invention, therefore, is the provision of a last to manufacture the type of shoe illustrated and described in my copending application Ser. 10 No. 204,727, filed July 11, 1927, which shoe will maintain normal feet in their normal condition and which will, at the same time, give the necessary support and correction to feet which are in need of such support and 15 correction.

In carrying out my present invention, and constructing my novel last, I utilize and combine several advantageous features therein, all of which features co-ordinate and 20 operate to produce a scientifically designed and proper last. Attempts have been made, for many years, to produce a last of this type, but none of these lasts, so far as I am aware, has been satisfactory in use, as all of these 25 lasts over-emphasized some particular feature and carried such feature to the extreme, rather than resulting, as my novel last does, in a well-balanced, scientifically correct shoe last.

My present novel last may be made as a 30 block last, or as a hinge last, with equal facility, either type of last being capable of incorporating all of the advantageous features herein set forth. To produce this desirable last, I provide, on the bottom thereof, 35 a pair of apexes, designed and arranged to create pockets in the shoe constructed thereon. These apexes are arranged to coincide with the position of the inner and outer balls of the feet of the wearer, and between the 40 apexes I provide a depression, the apexes being arranged on a diagonal line on the last bottom. This depression results, in the shoe constructed thereon, in a support for the metatarsal arch, by forming a raised surface 45 on the inside of the shoe, and is of great importance.

The principle of providing these apexes, resulting in pockets in the shoe, also eases the vamp line at the throat of the shoe, allowing an easy and natural break between the 50 toe and ball.

My novel last is also so constructed that all widths and sizes will have a standard height heel, and therefore all variation in 55 toe spring and heel pitch is thereby eliminated.

In order to provide for the longitudinal arch of the foot of the wearer, I cut the entire inside arch quite deep, particularly just in back of the ball. This deep cut arch is 60 accented in the construction of the shoe, and results in the natural support of the entire longitudinal arch of the foot. I also provide my novel last with increased fullness at the portion corresponding to the cuboid bone 65 of the foot, which will allow the foot to rest in a broad depression in the shoe, and will force the arch into the proper curved position. This construction of the last insures, in the completed shoe, against gaping of the 70 sides and slippage of the heel.

The width of the tread of the last, and resulting shoe, is designed to comfortably contain the toes and ball of the foot, while in no way detracting from the appearance of 75 the footwear. The roll on the toe of the last is a distinctive feature, and permits accommodation of the toes in a comfortable manner. This roll of the last terminates at the great toe, where it recedes, resulting in a 80 forepart of attractive appearance and pronounced style and character, in the completed shoe.

The back of the last, or heel curve, is so 85 pitched that in the resulting shoe there will be no chafing at the heel cord, and the entire heel will be seated uniformly without undue pressure in or on any one place.

A further and important feature of the present invention is the particular construction of the heel seat of the last, which is formed "mushroom shaped", or convex to a great degree. This results, in the shoe manufactured on such a last, in a deeply cupped heel seat, which will provide room for my 90 novel heel rest described in said copending application Ser. No. 204,727, thus allowing the fleshy part of the heel to not only fill out the entire surface of the heel seat, but also to rest comfortably and in normal position 95 on the heel rest, thus assuring a positive and comfortable fitting heel. This is also aided by the scientific construction of my novel last, which is so constructed and arranged as to maintain the correct balance between the arch 100 and the heel.

I believe that my last constructed as above briefly described, is novel, and I have therefore claimed the same broadly herein.

Further features of the invention, details 110 of construction, and advantages, will be hereinafter more fully pointed out and claimed.

Referring to the drawings, illustrating a preferred embodiment of my present invention,

- 5 Fig. 1 is a side elevation of my novel last;
- Fig. 2 is a bottom plan view of the last;
- Fig. 3 is a cross-sectional view on the line 3—3 of Fig. 1;
- Fig. 4 is a cross-sectional view on the line 4—4 of Fig. 1;
- 10 Fig. 5 is a cross-sectional view on the line 5—5 of Fig. 2; and
- Fig. 6 is a cross-sectional view on the line 6—6 of Fig. 1.

As shown in the drawings, my novel last is provided on its bottom faces with two apexes 1 and 2, between which is formed a depression 3. As will be seen, the apexes 1 and 2 are arranged on a diagonal line across the last bottom, to coincide with the relative 15 position of the inner and outer balls of the foot. The last utilized may be a hinge last, or a block last, or any type or style of last desired, since the novel features herein described may be applied with equal facility to 20 any existing type of last. In the shoe constructed on my novel last, pockets will be created by the apexes 1 and 2, into which the inner and outer balls of the foot will drop, thus adding greatly to the comfort and free 25 fitting qualities of the shoe made on said last. The depression 3 permits the formation of a desirable support for the metatarsal arch, by forming a raised surface on the inside of the shoe. The construction just described eases 30 the vamp line at the throat of the shoe, allowing an easy and natural break between the toe and ball. The entire inside or longitudinal arch 4 is cut quite deeply, and particularly is this so just in back of the ball or apex 35 1 at 5. The longitudinal arch extends to the rear of the last, substantially to the rear of the heel of the last as shown at 6, thus resulting, in the shoe manufactured on this last, in a natural support for the entire longitudinal 40 arch.

At the portion of the last corresponding to the cuboid bone of the foot, as shown at 7, the last is formed wide or full, forming a depression in the shoe constructed thereon into 45 which the foot of the wearer will rest and which will permit the high inside curve of the shoe to force the arch of the foot into a curved position. Also by forming the wide cuboid portion of the last, and by narrowing the waste of the last, as shown at 8, gaping of the sides and slipping at the heel is substantially if not entirely eliminated. The width of the tread, across the forepart of the last, is designed to result in a shoe which will 50 comfortably contain the toes and ball of the foot, while in no way detracting from the neat and attractive appearance of high grade foot wear.

The roll on the toe of the last, as shown at 9, permits accommodation of the toes in a com-

fortable manner, and terminates at the front of the last, at the point corresponding to the great toe of the foot, where it recedes. This also results, in the shoe made thereon, in an attractive and neat forepart of distinctive 70 style and character.

It will be instantly apparent that the bottom of this last is so designed as to result in a shoe which will be shaped to conform to the anatomy of the foot, the heel and ball-tread being so balanced that throwing of the foot into an abnormal position is eliminated. Any style of shoe, from oxfords to pumps, may be constructed on this type of last, and all of the advantageous features herein pointed 80 out will be obtained in such footwear. The back or heel curve 10 is so pitched that it causes no chafing at or on the heel cord, or "cord of Achilles" and the entire back of the heel will be seated uniformly without undue 85 pressure upon any one part or place.

The toe portion of the tread, as shown at 11, is formed substantially flat, or with but a slight convexity, thus permitting smooth and even seating and fitting of the forward part 90 of the foot in the shoe constructed on my novel last.

An important feature of the present last is the peculiar construction of the heel seat portion thereof, wherein, as will be seen at 95 12, I form the seat with an extreme convexity or roundness. This results, in the shoe built on this last, in a deeply cupped heel seat, permitting the application of my novel heel rest or cushion as explained more in detail in my 100 said copending application. This enables the flesh part of the heel to fill out the entire surface of the heel seat and to rest comfortably and in normal position on the cushion or heel rest. Thus a positive and comfortably 105 fitted heel is assured in the shoe. This is further aided and assisted by the present last, which is scientifically so constructed as to keep the correct balance between the arch and the heel, which will also result in a great re- 110 lief to the heel and spine of the wearer.

To the rounded heel seat 12 I may also, and preferably do, apply a clinching plate 13, of metal, secured to the heel seat by tacks or nails 14. The metal clinching plate 13 115 also corresponds to the extreme rounding of the heel seat, so that when the shoe is constructed thereon, it can be easily fitted over and around this rounded heel seat, resulting, as aforesaid, in the deeply cupped heel seat 120 desired in the shoe.

It will be readily apparent to those skilled in this art that I have devised a last containing many advantageous and orthopedic features, and yet a last which can be easily and economically manufactured, and which will result in a shoe that will add greatly to the health and foot comfort of the wearer. I have therefore claimed this last broadly in 125 the present application.

While I have necessarily described my invention somewhat in detail, it will be appreciated that I may vary the size, shape and arrangement of parts within reasonably wide limits without departing from the spirit of the invention.

My invention is further described and defined in the form of claims as follows:

1. A last of the kind described provided with a longitudinal instep arch extending from the ball of the toe portion to the rear end of the heel, and a pair of apexes on the bottom of said last to cause pockets to be formed in the shoe made on said last to accommodate the inner and outer balls of the foot.

2. A last of the kind described provided with a longitudinal instep arch extending from the ball of the toe portion to the rear end of the heel, a pair of apexes arranged on a diagonal line on the bottom of said last to cause pockets to be formed in the shoe made on said last to accommodate the inner and outer balls of the foot, the bottom of said last having a recess between said apexes to permit a metatarsal arch supporter to be formed in said shoe, the heel curve of said last being pitched to a predetermined degree.

3. A last of the kind described provided with a longitudinal instep arch extending from the ball of the toe portion to the rear end of the heel, a pair of apexes arranged on a diagonal line on the bottom of said last to cause pockets to be formed in the shoe made on said last to accommodate the inner and outer balls of the foot, the bottom of said last having a recess between said apexes to permit a metatarsal arch supporter to be formed in said shoe, the heel curve of said last being pitched to a predetermined degree, the outer cuboid extension of the last being so constructed as to provide a wide recess for the outer longitudinal arch of the foot in said shoe, and a heel seat of pronounced concavity to form in said shoe a deeply cupped heel seat.

4. A last of the kind described provided

with a longitudinal instep arch extending from the ball of the toe portion to the rear end of the heel, a pair of apexes arranged on a diagonal line on the bottom of said last to cause pockets to be formed in the shoe made on said last to accommodate the inner and outer balls of the foot, the bottom of said last having a recess between said apexes to permit a metatarsal arch supporter to be formed in said shoe, the heel curve of said last being pitched to a predetermined degree, the outer cuboid extension of the last being so constructed as to provide a wide recess for the outer longitudinal arch of the foot in said shoe, a heel seat of pronounced concavity to form in said shoe a deeply cupped heel seat, and a roll of greater than normal fullness on the toe of said last terminating and receding on the portion of the last corresponding to the great toe of the foot.

5. A last of the kind described provided with a longitudinal instep arch extending from the ball of the toe portion to the rear end of the heel and being of greatest depth at a point just back of the inner ball of the last, a pair of apexes arranged on a diagonal line on the bottom of said last to cause pockets to be formed in the shoe made on said last to accommodate the inner and outer balls of the foot, the bottom of said last having a recess between said apexes to permit a metatarsal arch supporter to be formed in said shoe, the heel curve of said last being pitched to a predetermined degree, the outer cuboid extension of the last being so constructed as to provide a wide recess for the outer longitudinal arch of the foot in said shoe, a heel seat of pronounced concavity to form in said shoe a deeply cupped heel seat, and a roll of greater than normal fullness on the toe of said last terminating and receding on the portion of the last corresponding to the great toe of the foot.

In testimony whereof, I have signed my name to this specification.

PAUL C. WOLFER.
